UNITED STATES PATENT OFFICE.

E. BARNHART, OF SHIPPENSBURG, PENNSYLVANIA.

SMUT-MACHINE.

Specification of Letters Patent No. 24,086, dated May 24, 1859.

To all whom it may concern:

Be it known that I, E. BARNHART, of Shippensburg, in the county of Cumberland and State of Pennsylvania, have invented a new 5 and Improved Smut-Machine; and I do hereby declare that the following is a full, clear, and exact description of the same, reference being had to the accompanying drawing, forming part of this specification, in 10 which—

Figure 1, represents a vertical central section of a smut machine constructed according to my invention. Fig. 2, is a horizontal section of ditto, the line x, x , in Fig. 1, indicating the plane of section. Fig. 3, is a section of the rotary disk and shell, taken in the line y, y , in Fig. 1, and looking up from below.

Similar letters of reference in the 3 views 20 indicate corresponding parts.

This invention consists in arranging in a hollow cylinder with fluted top and sides a rotary disk the surface of which is also fluted and to which a cylindrical fluted shell 25 is attached, which surrounds 4 wings placed at the under side of the disk so that the wheat or grain as it passes through the funnel on the disk is spread in all directions by means of the fluted surface of the same assisted by the fluted top and sides of the hollow cylinder and by the fluted shell, and that when so spread it is exposed to the blast 30 created by the wings at the under side of the disk so that the largest part of the dust and chaff is thrown out by the force of this blast before the grain enters the fan cylinder in 35 which it is exposed to a second and more powerful blast so that all the dirt and chaff are separated from the grain merely by the 40 action of the blast created by the two fans.

To enable those skilled in the art to fully understand, use and construct my invention I will proceed to describe it.

A, is a frame constructed of wood and 45 sufficiently strong for the purpose, and arranged in the center of its bottom is a step a , and in the central part of its top a journal box b , which form the bearings for a vertical arbor B, to which a pulley C, is rigidly 50 attached and which receives a quick rotary motion from some source. Firmly secured to the upper part of the arbor B, is the disk D, which is fluted on its upper surface, as clearly represented in Fig. 2, and to which 55 a fluted shell E, is attached, the outer diameter of which is equal to the diameter of

the disk, and which surrounds 4 wings c , which are rigidly attached to the under side of the disk. This disk rotates freely in a hollow cylinder F, the top and sides of 60 which are also fluted and to which access is had by a funnel G', which surrounds the arbor B, and this cylinder is of considerably larger diameter and it is also wider than the disk D, so that this latter and the shell 65 E, rotate therein without touching either top or bottom of the cylinder, and plenty of room is left between the outside of the shell E, and the inside of the cylinder F, and so that the blast created by the wings 70 c , can escape freely from under the shell E. The cylinder F, is provided with an opening d , in its side and a spout e , is attached thereto which serves to carry off the chaff and dust which are separated from the grain 75 by the action of the wings c , and another central opening is cut into the bottom of the cylinder F, which serves to let the grain out to the fan cylinder G, which rests on a platform f , in the frame A, and which is constructed in the usual manner, having a series of wings g , which are rigidly attached to and rotate with the arbor B, and which are surrounded by the cylindrical shell G, from which a spout h , leads into a channel H, 80 the upper part of which is divided by a slide i , and which is closed on the top and provided with outlets i , k , and l , the outlet i , being at the bottom of the channel for the purpose of discharging the good grain, and 85 the outlets R , and l , being in the upper portion of the channel, serving as escapes for the dust and chaff. 90

The slide I, serves to regulate the action of the blast, and if it is pushed up entirely 95 the full blast from the pan escapes through the openings i , and k , but if the action of the blast is found to be too powerful, the slide I, is drawn down so that the opening l , is brought in communication with the spout h , of the fan cylinder G, whereby the blast is divided and its action is rendered less effective. But if the slide I, is taken out altogether, the blast from the spout h , 100 goes right straight out through the opening l , and its effect is at its maximum. 105

The operation is as follows: Wheat or some kind of grain is introduced on the disk E, by the funnel G', and as it touches the fluted surface of the disk, and by the 110 action of the same against the top of the cylinder F, it is spread out and thrown out

between the fluted sides of the cylinder and the shell E, where it is exposed to the blast created by the wings c, under the disk D, and the lighter particles of dust and chaff contained in the grain are driven out by the spout e, while the good grain mixed with the heavier parts of the dirt and chaff is discharged into the fan cylinder G, where it is exposed to a second more powerful blast created by the wings g, and by this second blast, the effect of which is regulated by the slide I, all the dirt and chaff are driven out by the openings k, and l, in the channel H, and the good grain is discharged

through the opening i. By these means I am enabled to clean the grain perfectly in a very short time and without any waste.

What I claim as new and desire to secure by Letters Patent, is:

The disk D, arranged with the fluted shell E, and with the wings c, to operate in combination with the fluted cylinder F, which is provided with a spout e, substantially as and for the purpose specified.

E. BARNHART.
